Primary Examiner — T Chase Nelson*Assistant Examiner* — Sydney Margaret Parsley(74) *Attorney, Agent, or Firm* — Ralph E. Jocke;
WALKER & JOCKE(57) **CLAIM**

The ornamental design for a roofing plate, as shown and described.

DESCRIPTION

FIG. 1 is a cross sectional view of the roofing plate showing my new design;

FIG. 2 is a top view thereof.

FIG. 3 is a bottom view thereof.

FIG. 4 is a left side perspective view thereof; and,

FIG. 5 is a right side perspective view thereof.
